UNITED STATES PATENT OFFICE.

ALBERT B. CRONQUIST, OF PORTLAND, OREGON.

TOOL HOLDER.

Application filed December 14, 1925. Serial No. 75,308.

My invention relates to devices for holding inserted tools as a class.

The object of my invention is to provide such a device primarily for holding an inserted wrench jaw of special form, but also to hold a hammer head, screw driver and various other tools of like form. These tools are inserted in an oscillating member mounted in the end of the handle. 10 These objects, as well as other advantages, I attain by the construction, combination and arrangement of parts illustrated in the accompanying drawings which form a part hereof.

15 Fig. I is a plan view of the device, partly in section, with wrench jaw inserted in holding member.

Fig. II is a side view of the same.

20 Fig. III is a sectional view of the socket in the holding member.

Fig. IV is an illustration of a hammer head as inserted in the holding member.

Like characters refer to like parts in the views.

25 A handle of convenient form and dimensions is provided. The handle is composed of two like members 1-2 which are secured to each other by screws 3 and when in position form a casing for the parts to be described. In the upper end of the handle a holding member 4 is pivoted in bearings 5. The member 4 has a wedge-shaped socket 6, adapted to receive the arm 7 of a tool, such as the arm of the wrench jaw 8 or the arm 9 of the hammer head 10. The arm has a small recess in the edge as at 11. A pin 12 is transversely positioned in the socket 6 to engage the arm in its recess 11 and retain the arm in the socket. The pin is outwardly 30 actuated by a coil spring 13, the tension of which is sufficient to retain the pin in the recess 11 when opposed and to allow the arm to press the pin inwardly when inserted to operating position or withdrawn. The lower 35 rounded portion of the member 4 has peripheral ratchet teeth 14 along its edge. The member 4 is positioned to oscillate on its pivot sufficiently to allow its socket to assume a predetermined radial position between that of opposing positions transverse to the handle. Below the member 4 is a rod 15, vertically movable through an opening 16 in the casing in sliding engagement with the sides thereof, the opening being in the 40 upper portion of the handle. The rod is also rotatable in said bearings. On the up- per end of the rod 15 is an integral ratchet or pawl 17, provided with teeth 17^a along its upper edge, in alignment to engage the teeth 14 of the member 4. Below the ratchet 60 on the rod are opposing finger projections 18. The casing members have openings 19 to allow access to the projections 18. The casing members have a vertical recess 20 in their lower portion, within which a coil 65 spring 21 is placed. The lower end 22 of the rod 15 engages the upper end of the spring. Above the rod end 22 the rod has a circumferential groove 23 and a shoulder 24 formed therein. Within the casing are two 70 oppositely disposed levers 25 pivoted near their central parts in the casing on pivots 26, adjacent to the rod 15. The casing has openings 27 to allow these levers to move into and out of the casing. Upon the lower 75 ends of the levers are integral angled catches 28, positioned to allow them to pass into the groove 23 and engage the shoulder 24. Adjacent to the upper end of the lever are spring guides 29-29 positioned in the casing 80 to retain the lever and its catches in alignment with the rod.

77 The device is operated as now described. The upper ends of the levers 25 are pushed inwardly, thus causing the catches 28 to move outwardly and release the rod, which has its ratchet or pawl teeth 17^a retained in engagement with the teeth 14 of the member 4 by the upward tension of the spring 21. The rod is then pushed downwardly, by applying 85 the fingers to the projections 18, and held until the member 4 is rotated to a desired position, for instance from longitudinal to transverse position shown by dotted lines in Fig. I. Thereupon the finger grip is released, the spring 21 forces the rod upwardly and the ratchet teeth into renewed engagement with the teeth 14 and the tool in the member is set at any angle between the transverse positions on either side of its 90 pivot. The wrench jaw 8 is inserted in the socket 6 and retained there by the pin and spring means adjacent, which are arranged to allow of its easy insertion and removal while the member 4 is in any radial position. 95 This tool may be replaced in like manner by various tools having an arm 7 as shown in the wrench jaw and like arm 9 of the hammer 10 in Fig. IV. Thus the device may have a screw driver, lifting claw, etc. It 100 will also be observed that while the teeth are engaged the member 4 can be moved 105

along the ratchet from a longitudinal position in one direction to transverse position and is retained from moving reversely by the ratchet teeth. If desired to have the member 4 oscillate reversely, the rod is released as described and rotated until the ratchet is reversed.

Its usefulness as a wrench is highly important, as it will be observed that the wrench jaw may be set at any angle and any size of wrench jaw employed. Thus a nut which is in such position that the usual transverse jaw cannot be applied to it, and allow movement of the handle, can be moved by a wrench jaw in longitudinal or angled position. It will be observed also that the different sizes of jaws are compact and may be carried about easily, as well as other indicated tools. The device is distinctly new and useful, as well as economical in manufacture, thereby assuring a combination tool holder of moderate expense to the user. The device has been reduced to practice and found to be entirely practical and operative as described and illustrated.

I claim—

1. In a tool holder, the combination of a casing handle, an oscillating member pivoted near one end of the handle, said member having ratchet teeth along its edge a convenient distance and an outwardly opening wedge-shaped socket, the member being adapted to position the socket at any angle above and on a line transverse to the handle and toward either side thereof; a slidable and rotatable rod, positioned longitudinally in the handle, and having an integral pawl on one end arranged and adapted to engage the teeth of said member and retain its socket rigidly in a selected position on a radial line from the member pivot and longitudinal direction of the handle and to release said member from such engagement, levers pivoted in said handle, adapted and arranged to engage said rod, retain its pawls in engagement with said member and release same therefrom, and a spring positioned with respect to the opposite end of the rod to allow the pawls of the rod to be pressed thereby into engagement with the ratchet teeth.

2. In a tool holder, the combination of a casing handle, an oscillating member pivoted near one end of the handle, said member having ratchet teeth along its edge a convenient distance and an outwardly opening wedge-shaped socket, the member being adapted to position the socket at any angle above and on a line transverse to the handle and toward either side thereof; a slidable and rotatable rod, positioned longitudinally in the handle, and having an integral pawl on one end arranged and adapted to engage the teeth of said member and retain its socket

rigidly in a selected position on a radial line from the member pivot and longitudinal direction of the handle and to release said member from such engagement, levers pivoted in said handle, adapted and arranged to engage said rod, retain its pawls in engagement with said member and release same therefrom, and a spring positioned with respect to the opposite end of the rod to allow the pawls of the rod to be pressed thereby into engagement with the ratchet teeth.

3. In a tool holder, the combination of a casing handle, an oscillating member pivoted near one end of the handle, said member having ratchet teeth along its edge a convenient distance and an outwardly opening wedge-shaped socket, the member being adapted to position the socket at any angle above and on a line transverse to the handle and toward either side thereof; a slidable and rotatable rod, positioned longitudinally in the handle, and having an integral pawl on one end arranged and adapted to engage the teeth of said member and retain its socket rigidly in a selected position on a radial line from the member pivot and longitudinal direction of the handle and to release said member from such engagement, levers pivoted in said handle, adapted and arranged to engage said rod, retain its pawls in engagement with said member and release same therefrom, and a tool adapted to be received and secured in the member socket.

4. In a tool holder, the combination of a casing handle, an oscillating member pivoted near one end of the handle, said member having ratchet teeth along its edge a convenient distance and an outwardly opening wedge-shaped socket, the member being adapted to position the socket at any angle above and on a line transverse to the handle and toward either side thereof; a slidable and rotatable rod, positioned longitudinally in the handle, and having an integral pawl on one end arranged and adapted to engage the teeth of said member and retain its socket rigidly in a selected position on a radial line from the member pivot and longitudinal direction of the handle and to release said member from such engagement, levers pivoted in said handle, adapted and arranged to engage said rod, retain its pawls in engagement with said member and release same therefrom, a tool adapted to be received and secured in the member socket, and means in the member arranged automatically to secure such tool in the socket and allow its release therefrom.

ALBERT B. CRONQUIST.
